UNITED STATES PATENT OFFICE

WILLIAM KEMP, OF ST. LOUIS, MISSOURI

GAS ANALYZER

Application filed December 4, 1931. Serial No. 578,918.

My invention relates to a gas analyzer and particularly to improvements in the form of analyzer shown and described in Patent No. 1,727,544 granted to me September 10, 1929.

5 One object of my invention is to provide improved means for securing the diffusion plate in position so as to form an effective gas-tight seal by simple and economical means and at the same time to provide for easy 10 removal and replacement of the plate for the purpose of cleaning or replacement.

Another object of my invention is to provide means for preventing the creeping of caustic potash or other gas absorbent material 15 over the surface of the diffusion plate with resultant reduction in efficiency of the analyzer.

In the accompanying drawing, which illustrates one form of gas analyzing apparatus 20 made in accordance with my invention, Figure 1 is a vertical longitudinal section; Figure 2 is a top plan view of the absorption chamber; and Figure 3 is a detail view of the diffusion plate and its elastic peripheral 25 binding, a portion of the latter being broken away.

The general construction of the apparatus is like that shown and described in my prior patent above referred to, comprising 30 an absorption chamber, a diffusion plate, means for supplying to the diffusion plate a uniform flow of the flue gas or other gaseous mixture to be analyzed, and an indicating or recording device communicating with the absorption chamber and actuated by the variations of gas pressure therein.

The absorption chamber is preferably in the form of a rectangular steel tank 5 and contains the absorption material 6, usually 40 a solution of caustic potash (KOH) in water. Formed in the top of the tank is a circular opening 7 surrounded by a boss 8 either formed integral with or secured to the tank. The upper edge of the boss forms an annular 45 seat for the diffusion plate 9. This plate is circular in form and of a diameter substantially equal to the outer diameter of the boss.

Enclosing the periphery of the diffusion plate is a resilient binding consisting of a 50 vertical web 10 and a pair of annular flanges

11 extending inwardly therefrom. This binding may be made of rubber or similar resilient impervious material. The lower flange rests upon the boss and the upper flange contacts with an annular seat 12 on the under side of a cover plate 13. Eye bolts 14 are attached to the boss by pins 15 and extend through lugs 16 on the cover. Thumb nuts 17 on the threaded ends of the bolts serve to hold the cover firmly in contact with the binding and thus insure a gas-tight seal between both the tank and the diffusion plate and the latter and the diffusion chamber 4 formed between the plate and the cover.

In analyzers of this type the caustic potash or other gas absorbent material tends to creep along the walls of the tank to the diffusion plate and then spread inwardly over the lower face of the plate, reducing its effective area. To overcome this objectionable feature, I form in the inner wall of the boss an annular groove, preferably slightly inclined downwardly, as shown, and place in this groove a filling 18 of moisture repellent material, such as paraffin wax. The repellent ring intercepts the absorbent caustic potash and so protects the diffusion plate from contamination thereby.

The gas to be analyzed is supplied to the diffusion chamber through a supply pipe 19 and escapes through an outlet opening 20 at the opposite side of the chamber. The absorption chamber communicates through a pipe 21 with an instrument 22 which indicates or records the variations of pressure in the absorption chamber due to the percentage of absorbable gas in the mixture supplied to the diffusion chamber.

It will be seen that while my analyzer is simple in construction, an effective seal is provided for the diffusion plate and said plate may be readily removed and replaced for the purpose of cleaning its upper surface which may receive deposits of carbon from the flue gases passing over it. Further, the lower face of the plate is effectively protected from contamination by the caustic potash of the absorption liquid.

Having fully described my invention, what

I claim as new and desire to secure by Letters Patent of the United States is:

1. In a device of the class described, an absorption chamber provided with a seat, a diffusion plate, an impervious binding surrounding the periphery of said plate and having inwardly extending flanges overlapping both faces thereof, one of said flanges bearing on said seat, a cover contacting with the other 10 of said flanges, and clamping means for securing the cover in position.
2. In a device of the class described, an absorption chamber provided with a seat, a diffusion plate, a binding for said plate 15 formed of resilient impervious material comprising a web enclosing the periphery of the plate and a pair of integral flanges overlapping the faces thereof, one of said flanges bearing on said seat, a cover contacting with 20 the other of said flanges, and clamping means for securing the cover in position.
3. In a device of the class described, an absorption chamber having an opening in the top thereof, a boss surrounding said opening, 25 the edge of said boss forming a seat face, an absorption disk, a binding for said disk formed of resilient impervious material comprising a web enclosing the periphery of the disk and a pair of integral flanges over- 30lapping the faces thereof, one of said flanges bearing on said seat, a cover contacting with the other of said flanges, bolts carried by said boss, and nuts on said bolts and engaging the cover to secure the same in position.
- 35 4. In a device of the class described, the combination with a tank containing an absorption liquid, of a diffusion plate supported from said tank, and a moisture repellent barrier interposed between the liquid 40 and the plate to prevent access of the former to the latter by creepage along the walls of the tank.
- 45 5. In a device of the class described, the combination with a tank containing an absorption liquid, an opening in the top of said tank surrounded by a boss, a groove formed in the inner wall of said boss, a filling of moisture repellent material in said groove, a diffusion plate supported on said boss, and 50 means for clamping said plate in position.

In testimony whereof, I hereunto affix my signature, this 1st day of December, 1931.

WILLIAM KEMP.
